AUTOMATIC BURGLAR, FIRE, OR LIKE
ALARMEdred Rabjohn Mountstephen, Southend-on-Sea,
EnglandApplication November 2, 1937, Serial No. 172,461
In Great Britain November 4, 1936

5 Claims. (CL. 179—5)

This invention relates to automatic burglar or fire alarms of the kind comprising a gramophone or like sound reproducing device operatively connected with a telephone and associated with means automatically to establish communication with a police, fire or other station and to transmit a suitable message to said station upon the occurrence of a burglary or fire.

A prior United States Patent No. 2,090,574 describes an alarm of this character in which the unauthorized opening of a door, window, safe or the like, or the operation of a thermostat due to an abnormal rise in temperature, operates an electro-magnet which releases trip mechanism whereby means are set into operation to establish a connection between the alarm device and the telephone system and to start the gramophone motor. The gramophone motor, upon being started, operates mechanism which successively dials an emergency signal to establish communication with the appropriate station, lowers the sound box onto a sound reproducing record to produce the message or alarm to be transmitted, returns the sound box to the commencement of the record and finally disconnects the device from the telephone system.

The mechanism for effecting these various operations is of a relatively complicated construction and the object of the present invention is to provide an improved simplified construction of driving and control mechanism for effecting the above mentioned operations and an improved dialling mechanism whereby the apparatus is simplified and the reliability and certainty of its operation under all conditions is enhanced.

According to the invention the means for effecting the necessary sequence of operations, including the dialling means and the sound box lifting and lowering means, are operated by a common transmission shaft or driven element actuated by the gramophone motor.

In order that the invention may be more clearly understood one particular embodiment thereof will now be described by way of example, with reference to the accompanying drawings wherein:

Figure 1 is a plan view of the apparatus according to the invention.

Figure 2 is a side elevation looking in the direction of the arrow II in Figure 1.

Figure 3 is a side elevation of the dialling mechanism showing the parts in the operative position.

Figure 4 is a side elevation, looking in the direction of the arrow IV in Figure 1, of the transmission unit.

Figure 5 is a similar view of the lifting and lowering mechanism for the sound box.

Figure 6 is a side elevation looking in the direction of the arrow VI in Figure 1, and

Figure 7 is a diagram of the wiring circuit.

In the construction shown in these drawings the driving mechanism consists of a self contained transmission unit, generally designated A, comprising a common vertical transmission shaft 8 driven direct from the turntable spindle 9 of the gramophone and a pair of horizontal shafts 10 and 11 driven from said transmission shaft, for respectively driving the dialling mechanism, generally designated B, and operating the mechanism, generally designated C, for lifting and lowering the sound box onto the sound record. The turntable spindle 9, the transmission shaft 8 and the two shafts 10 and 11 are interconnected by suitable gearing and said shafts 8, 10 and 11 are mounted in a common bracket 12 rigidly secured to the base plate 13 of the apparatus.

On the upper end of the common transmission shaft 8, of the transmission unit A, is mounted a toothed wheel 14 which meshes with a pinion 15 rigidly mounted on the turntable spindle 9. On the lower end of the transmission shaft 8 is a bevel wheel 16 which meshes with a second bevel wheel 17 mounted on one end of the shaft 10 which, through the intermediary of a pinion 18 mounted on its opposite end, drives the dialling mechanism B which is hereinafter fully described. Intermediate the ends of the transmission shaft 8, between the toothed wheel 14 and the bevel wheel 16, is mounted a worm 19 which engages a toothed wheel 20 securely mounted on the shaft 11 which operates the mechanism C, which is hereinafter fully described, for lifting the sound box and lowering it onto the gramophone record. Also mounted on the shaft 11 is a cam 21 by means of which the dial is moved into operative position as hereinafter described.

The dialling mechanism, generally designated B, comprises an annular rack 22 rigidly mounted in suitable bearings in a supporting bracket 24 secured to the base plate 13 of the apparatus. On the lower end of the spindle 23 is mounted a radial arm 25. The annular rack 22 is arranged concentrically above a standard telephone dial 26 and is driven continuously by the pinion 18 mounted on the driving shaft 10 of the transmission unit A, so that the radial arm 25 is caused to rotate continuously around the face of the dial 26.

The dial 26 is mounted on one end of an arm 55

or plate 27 which is pivoted at 28 to the base plate 13 of the apparatus in such a manner as to pivot in a vertical plane, whereby said dial can be raised to bring a pin 29 mounted thereon into the path of the continuously rotating arm 25 (Figure 3). The pin 29 or the like is mounted in the aperture of the dial which normally corresponds to the "0" of a standard telephone dial.

The dial is raised and lowered as desired by the action of the cam 21 which, during the rotation of the shaft 11 upon which it is mounted, actuates a lever 31 which is pivoted at 32 to the bracket 12 and which in turn operates a rockable lever 33 which is pivoted at 34 and extends below a finger 35 pivotally mounted on a pin 36 mounted on the vertically movable plate or arm 27 carrying the dial 26. The pivoted lever 31 is provided with a projection 30, with which the cam 21 engages, and extends above the outer end of the rockable lever 33. The adjacent ends of the levers 31 and 33 are held against lateral displacement by means of a slotted guide member 37.

In operation the transmission unit A rotates the cam 21 and the radial arm 25 mounted above the dial 26 continuously as hereinbefore described. During its rotation the cam 21 engages the projection 30 on the lever 31 and causes said lever to move about its pivot 32 and to press downwardly against the end of the rockable lever 33 which is thus caused to rock about its pivot 34, whereupon the opposite end of said rockable lever 33 is moved upwards and since it is located below the finger 35 mounted on the plate 27 carrying the dial 26, lifts said dial and thus brings the pin 29 mounted thereon into the path of the rotating radial arm 25. The pin 29 is thus engaged by the rotating radial arm 25 whereby the dial 26 is rotated in a clockwise direction until the cam 21, continuing its rotation, moves out of engagement with the lever 31 when the dial 26 drops under its own weight, or with the aid of a spring (not shown), and lowers the pin 29 out of the path of the rotating radial arm 25 to permit the dial to rotate in an anti-clockwise direction to its initial position. It will be understood that by suitably shaping the cam the dial can be lifted and lowered any desired number of times and can be maintained in its lifted or operative position for any duration. The actual number of times the dial is lifted and lowered and the precise duration it is maintained in its lifted or operative position, however, will depend upon the number of the digits in the number to be dialled, and the value of each of said digits respectively; thus the cam is shaped according to the number or emergency signal to be dialled. In the construction shown in the drawings the cam is shaped to lift the dial twice and to maintain the dial in its lifted or operative position firstly, for the period necessary for dialling the number "2" and secondly for the period necessary for dialling the number "0", the number "20" being assumed, for the sake of example, to represent the emergency dialling symbol.

As the spindle 11 upon which the cam 21 is mounted, rotates continuously, it is necessary that the dial 26 should be disconnected from the dial-lifting lever 33 immediately after the dialling operation, that is to say as soon as the dialling of the emergency signal has been effected, so as to prevent the dialling operation from being repeated when the cam 21 returns to its normally operative position. For this purpose the finger 35, which is pivoted at 36 and below one end of which the rockable dial-lifting lever 33 engages, projects at its opposite end into the path of the pin 29 mount-

ed on the dial 26 whereby at the end of the dialling operation, that is when "0" is dialled in the machine illustrated, the pin 29 contacts with the finger 35 and rotates it about its pivot 36 thereby moving it out of engagement with the rockable dial lifting lever 33 into the position shown in broken lines (Figure 1), whereupon the lever 31, which is normally held by the rockable lever 33 in the position shown in full lines in Figure 4 falls into the position shown in broken lines in Figure 4 in which position the projection 30 formed thereon no longer projects into the path of the cam 21.

If desired the dial 26 may be disconnected from the dial lifting lever mechanism 33, 31, 20 by separate mechanism operated direct from the cam 21.

After the dialling operation has been completed, and communication with the desired station thus established, and after the mechanism operated by the cam 21 is disconnected therefrom as described above, the sound box of the gramophone is lowered onto the sound record to produce the message or alarm. This is effected by the mechanism, indicated generally at C, which is operated by the shaft 11.

The sound box 38 is mounted on a tone arm 39 which opens into an enclosed housing or casing 40 in which is housed the microphone or transmitter which is arranged in the telephone circuit as indicated in the circuit diagram shown in Figure 6. The sound box 38, the tone arm 39 and the casing 30 or housing 40 for the microphone are built as a single unit, preferably of the character described in our co-pending application No. 172,462 which is mounted on a rod 41 rotatably mounted in a member 42 which is itself pivoted at 43 to a bracket 44, whereby said tone arm unit can pivot both in a horizontal plane, to enable the sound box to move across the sound record, and in a vertical plane, to enable the sound box to be lowered onto and lifted from said record. On the lower end of the rod 41 is a plate 45 which, when the sound box is in its raised position above the commencement of the sound record, lies parallel to and engages a stop bar 46. The sound box is normally held in this position by a supporting member 47 pivotally mounted in the bracket 44 and provided with a seating surface 48 for a roller 49 mounted at the lower end of an arm 50 which is integral with the member 42 pivoted in the bracket 44 and in which the rod 41 carrying the tone arm unit is mounted. The supporting member 47 and the arm 50 are arranged in the same vertical plane as a pin or cam 51 rigidly mounted on the operating shaft 11 of the transmission unit A. The pivot of the supporting member 47 is provided with a downwardly projecting extension 52 forming a handle by means of which the said member 47 can be moved into position when setting the machine ready for operation; also the operating shaft 11 is provided at its opposite end with an indicator 53 for use in setting the machine ready for operation.

In operation, the operating shaft 11 and with it the pin or cam 51 are continuously rotated by the transmission unit A, as hereinbefore described. During its rotation the pin or cam 51 first engages the supporting member 47 and pushes it out of engagement with the roller 49 of the arm 50 and then engages said roller 49. As the pin or cam 51 moves under the roller 49 the arm 50 is gradually lowered whereby the sound box is gradually lowered onto the commencement of the sound record to produce the message or alarm to be transmitted, and the plate 45 is moved out of engagement.

ment with the stop bar 46, (Figure 5). As the message or alarm is being transmitted the sound box travels across the record and at the same time rotates the rod 41 in the member 42. When the 5 sound box reaches the end of its travel across the record, the rod 41 will have been rotated to such an extent that the plate 45, mounted on the lower end thereof, will have moved into an angular position relative to the stop bar 46, and the pin or 10 cam 51 will have again reached the position where it engages the roller 49. When the pin then engages the roller 49 the arm 50 will be raised and cause the sound box to be lifted off the sound record. During this latter operation the plate 45 15 is again moved into engagement with the stop bar 46 but, owing to their relative angular positions, only one edge of said plate 45 will engage the stop bar 46 and, owing to the pressure of the plate 45 against the stop 46, the rod 41, on which the said 20 plate 45 and the tone arm unit of the gramophone are mounted, is caused to rotate until the plate 45 is again parallel to the stop bar 46 and the sound box is again positioned over the commencement of the record. At this stage the pin 25 or cam 51 will again gradually lower the arm 50 whereby the sound box 38 is again lowered onto the commencement of the record to repeat the message or alarm. The message or alarm is repeated continuously in this manner until the 30 gramophone motor runs down when the alarm device is disconnected from the telephone system as hereinafter described.

The burglar or fire alarm according to the invention is adapted to be connected to the telephone system by means of a multi-pole switch 54, which however, is normally open so that the alarm device is completely disconnected from the telephone system except when it is actually in operation. The switch 54 is closed to connect the device with the telephone system automatically when it is set into operation and is automatically opened again, as hereinafter described, to disconnect the device from the telephone system after the message has been transmitted and repeated as described above.

The mechanism for setting the alarm device into operation is illustrated in Figure 6 and generally designated D in Figure 1, and comprises trip mechanism formed by the armature 55 of an electro-magnet 57 and a catch or abutment 56 mounted on a double arm angular lever 58 provided at its outer free end with a weight 59 and pivoted at its opposite end at 13. Below one arm of the double arm lever 58, and in the same 55 vertical plane, is a catch 60 which engages a stop 61 on the gramophone turntable. The catch 60 is formed on one end of a pivoted lever 62 having at its opposite end a weight 63 which tends to hold the said catch 60 in engagement with the stop 61 on the gramophone turntable. The catch 60 is adapted to be moved out of engagement with the stop 61, to start the gramophone motor, by the double arm lever 58 when said lever falls into the position shown in broken lines 60 in Figure 6 upon the tripping of the trip mechanism 55, 56 as hereinafter described.

Below the outer end of the lever 58, and in the same vertical plane as the weight 59, is a 70 member 64, 65 which is pivoted at 66 and which is adapted to close the switch 54, for connecting the alarm device with the telephone system, when in the position shown in broken lines in Figure 6, into which position it is moved by the weighted lever 58 when the latter is released by the trip 75

mechanism 55, 56. The parts 64 and 65 of the switch closing member are pivoted together at 67 so that the part 64 can be pivoted upwardly and rearwardly to facilitate the return of the double arm lever 58 when the device is reset. 5 The forward and downward pivoting of the part 64 is limited by the projection 11 which engages below the part 65, said part 64 however, is normally held in this position by a light spring 72. The part 65 is provided with an element 70 which, 10 during operation, forces the resilient contacts of the switch 54 together to thus close said contacts. The part 64 of the switch-closing member 64, 65 is provided with a hooked end which, when the said member is moved into the closed position 15 shown in broken lines in Figure 6, engages below a catch formed on the armature 68 of an electro-magnet 69 whereby the switch 54 is held in the closed position.

As mentioned above the switch 54 is maintained in the closed position to connect the alarm device with the telephone system while the message or alarm is being transmitted, but after the message or alarm has been transmitted is again opened to finally disconnect the device from the 20 telephone system. The latter operation is effected, when the gramophone motor runs down by a knife switch 74, 75, Figure 1, which closes the circuit of the electro-magnet 69, which is thus energised so that the armature 68 is attracted and releases the member 64, 65 whereby 25 said member returns to its initial position, due to the resilient action of the switch 54, and said switch is opened.

The knife switch comprises members 74 and 35 75. The member 74 is pivoted at 76 to the base plate 13 and provided at its inner end with a fork-like part between the arms of which the edge of a disc 77 of the governor of the gramophone motor extends. When the motor is running at full speed the said member 74 of the knife contact is moved by the governor into the position shown in broken lines in Figure 1. The member 75 of the knife contact consists of two 40 spring blades pivoted together at 78 to the bracket 24 and is connected by a lever 79 to the finger 35 pivotally mounted on the dial 26, whereby 45 said member 75 is moved into the position shown in broken lines in Figure 1, that is into the path of the member 74, when said finger 35 is moved 50 at the end of the dialling operation as described above. In operation the two members 74 and 75 of the knife contact, which are initially in the 55 position shown in full lines in Figure 1, are when the device is set into operation, moved into the position shown in broken lines in the manner described, the member 74 being moved into such position first. The members 74 and 75 remain in this position until the gramophone motor runs down when the governor of the motor moves 60 the member 74 between two contact points (one of which is shown at 80 in Figure 1) on the member 75 whereby the circuit of the electro-magnet 69 is closed and the switch 54 thereby opened as 65 previously described.

The telephone circuit, that is the circuit in which the telephone dial 26, microphone 40 and the switch 54, and the circuits in which the electro-magnets 57 and 69 and knife switch 74, 75 are arranged, is illustrated diagrammatically in 70 Figure 7.

The electro-magnet 57, which releases weight 75 operated mechanism for setting the alarm into operation and closing the switch 54 for connecting the machine with the telephone line, is con-

nected with the terminals 4, 3 and the electro-magnet 69 which operates to open the switch 54 finally to disconnect the machine from the telephone line, is connected with the terminals 2, 3 through the mechanically operated knife switch 74, 75. The terminals 4, 5 are connected with the telephone line upon the closing of the switch 54, the connection from the terminal 5, through the telephone circuit being through the primary winding of an inductance coil 81, the switch 54 via contacts *a*, *b*, *c*, the secondary winding of the coil 81, the condenser 82, the switch 54, via contact *d*, the dial 26 and microphone 40 back through the switch 54, via contacts *e*, *c*, the inductance coil 81, condenser 82 to the terminal 4.

The operation of burglar or fire alarm according to the invention is as follows:

The electro-magnet 57 is energised, in any known manner, upon the unauthorized opening of a door, window, safe or the like or by the action of a thermostat upon an abnormal rise in temperature, whereby the trip mechanism 55, 56 is operated and the weighted lever 58 thereby released. The lever 58 then falls into the position shown in chain dotted lines in Figure 6 and during its fall first moves the catch 60 out of engagement with the stop 61 on the gramophone turntable to start the gramophone motor and then move the member 64, 65 into the position shown in chain dotted lines in Figure 6 to close the switch 54 and thereby connect the alarm device with the telephone system. The gramophone motor thus being set into operation moves the member 74 of the knife switch 74, 75 into the position shown in chain dotted lines for the purpose specified and simultaneously drives the transmission mechanism A. The cam 21 mounted on the shaft 11 of the transmission unit A then operates the lever mechanism 34, 33, 35 to lift the dial into operative position whereupon the dialling operation is effected, as described above, and communication with the desired station established, after which the elements 35, 79 are actuated to disconnect the dial from the dial lifting mechanism 38, 31, 21 and to move the member 75 of the knife contact into the position shown in chain dotted lines. After the above operations have been completed the pin or cam member 51 moves the supporting member 47 away from the arm 58 and moves under the roller 49 of said arm 58 to gradually lower the sound box 38 onto the record, as above described, whereupon the message or alarm is transmitted to the police, fire, or other station with which communication has been established. As the sound box travels across the sound record during the producing and transmitting of the message or alarm, the pin or cam 51 moves into position again to engage the roller 49 of the arm 58, the arrangement being such that the said pin or cam 51 reaches the roller 49 at or about the time the sound box reaches the end of its travel across the record. The sound box is then lifted and returned to the commencement of the record as described above, when the message or alarm is again produced and transmitted to the desired station. This operation is thus repeated continuously until the gramophone motor runs down when the member 74 of the knife switch passes through the spring blades of the member 75 and thus closes the circuit of the electro-magnet 69 which is thus energised with the result that its armature 68 is attracted and releases the hook 76 part of the member 64, 65 whereby the switch 54

is opened and the device thus disconnected from the telephone system.

It will be clearly understood that the ratio of the gearing of the transmission unit A must be such that the shafts 10 and 11 drive the mechanism B and C respectively, at predetermined relative speeds, and that the cam 21 for operating the dialling mechanism B, and the pin or cam 51 for operating the mechanism C, for lifting and lowering the sound box onto the record, must be so arranged on the shaft 11 relatively to each other that the various operations are effected in the desired sequence.

What I claim and desired to secure by Letters Patent is:

1. In an automatic alarm device including a gramophone having a record carrying turntable and a driving shaft therefor, said gramophone further having a sound box supported for movement into and out of engagement with a record on said table, the combination with means to effect raising and lowering of the sound box, means to swing said sound box across said table, a signal transmitting device including a dial, a shaft driven from said turntable shaft, and a plurality of gearings transmitting movement from said driven shaft to the sound box controlling mechanism and the dialing mechanism.

2. In an automatic alarm device including a gramophone having a record carrying turntable and a driving shaft therefor, said gramophone further having a sound box supported for movement into and out of engagement with a record on said table, the combination with means to effect raising and lowering of the sound box, means to swing said sound box across said table, a signal transmitting device including a dial, a shaft driven from said turntable shaft, a bevelled gear on said driven shaft, a third shaft extending laterally from the driven shaft, a bevelled gear on the third shaft meshing with the bevelled gear on the driven shaft, a gear fixed to the movable element of the dialing device, and a gear on the third shaft meshing with the last mentioned gear.

3. In an automatic alarm device including a gramophone having a record carrying turntable and a driving shaft therefor, said gramophone further having a sound box supported for movement into and out of engagement with a record on said table, the combination with means to effect raising and lowering of the sound box, means to swing said sound box across said table, a signal transmitting device including a dial, a shaft driven from said turntable shaft, a bevelled gear on said driven shaft, a third shaft extending laterally from the driven shaft, a bevelled gear on the third shaft meshing with the bevelled gear on the driven shaft, a gear fixed to the movable element of the dialing device, a gear on the third shaft meshing with the last mentioned gear, and other gearing actuating the tone arm controlling means.

4. In an automatic alarm device including a gramophone having a record carrying turntable and a driving shaft therefor, said gramophone further having a sound box supported for movement into and out of engagement with a record on said table, the combination with means to effect raising and lowering of the sound box, means to swing said sound box across said table, a signal transmitting device including a dial, a shaft driven from said turntable shaft, a bevelled gear on said driven shaft, a third shaft extending laterally from the driven shaft, a bevelled gear on the third shaft meshing with the bevelled gear on the driven shaft, a gear fixed to the movable element of the dialing device, a gear on the third shaft meshing with the last mentioned gear, and other gearing actuating the tone arm controlling means.

5 elled gear on the third shaft meshing with the bevelled gear on the driven shaft, a gear fixed to the movable element of the dialing device, a gear on the third shaft meshing with the last mentioned gear, and other gearing actuating the tone arm controlling means, said other gearing including a driving shaft for the tone arm controlling means, a worm wheel on said driving shaft, and a worm on said driven shaft meshing with said worm wheel.

10 5. In an automatic alarm device including a gramophone having a record carrying turntable and a driving shaft therefor, said gramophone further having a sound box supported for movement into and out of engagement with a record on said table, the combination with means to effect raising and lowering of the sound box, means to swing said sound box across said table, a signal transmitting device including a dial, a shaft

driven from said turntable shaft, a bevelled gear on said driven shaft, a third shaft extending laterally from the driven shaft, a bevelled gear on the third shaft meshing with the bevelled gear on the driven shaft, a gear fixed to the movable element of the dialing device, a gear on the third shaft meshing with the last mentioned gear, other gearing actuating the tone arm controlling means, said other gearing including a driving shaft for the tone arm controlling means, a worm wheel on said driving shaft, a worm on said driven shaft, a camming disk fixed on the driving shaft for the tone arm controlling means, means to raise and lower the gear on the dialing mechanism into and out of mesh with the gear on the third shaft, 15 and operating means for the last mentioned means controlled by said camming disk.

EDRED RABJOHN MOUNTSTEPHEN.
